AUTOMATIC CONTROL FOR WASTE HEAT UTILIZERS

Felix Saco, Jr., West Hartford, and William R. Williamson, Hartford, Conn., assignors to The Maxim Silencer Company, Hartford, Conn., a corporation of Connecticut

Continuation of application Serial No. 426,868, January 15, 1942. This application June 19, 1944, Serial No. 541,036

11 Claims. (Cl. 122—456)

1

This invention relates to apparatus for utilizing the waste heat of exhaust gases from internal combustion engines, or other low temperature gas source, and in particular is concerned with an automatic control for a waste heat boiler system.

This application is a continuation in part of our previously filed case Serial No. 380,022, Patent No. 2,397,208 for "Waste heat utilizer" filed February 21, 1941, and is a continuation of abandoned application Serial No. 426,868 for "Automatic control for waste heat utilizer" filed January 15, 1942.

An object of this invention is to reduce the heat transfer between the gases and the water in the boiler by varying the amount of contact surface in accordance with the output of steam desired. Other and further objects will appear from the description and claims.

In this system the heat transfer is controlled by varying the contact area between the water and heating surface by means of a pressure reducing valve and drum external to the heating section of the boiler.

The manner in which this is done will be apparent from the following description of the apparatus shown in the accompanying drawings, in which

Fig. 1 is a diagrammatic view of the waste heat control system with a preferred form of connection between the boiler and the drum controlling the water feed;

Fig. 2 is a view on line 2—2 of Fig. 1;

Fig. 3 is a diagram of the system arranged with the boiler in vertical position, the return line being attached as for a gravity feed system;

Figs. 4, 5, 6, 7 and 8 show diagrammatically alternative arrangements for conducting steam through the water control tank; and

Fig. 9 shows a modification in the steam line to the utilizing system.

The waste heat boiler 1, shown in outline in Fig. 1, is preferably made according to one of a variety of constructions as detailed generally and specifically in our above-mentioned application Serial No. 380,022, Patent No. 2,397,208, filed February 21, 1941, for "Waste heat utilizer" and of which the present application is a continuation in part. A cross section showing the general nature of a boiler is shown in Fig. 2. As shown in these views it generally comprises an outer cylindrical shell 2 and an inner cylindrical shell 3 spaced from it and providing between the two shells a water jacket 4 to which water is fed through an inlet pipe 5 (Fig. 1)

and from which steam or a mixture of steam and water is passed through outlet pipe 6 (Fig. 1). The surface area of shell 3 contacting the water in jacket 4 is heated by the exhaust gases entering through a tube 13 into a chamber 7 formed by a partition 8 dividing the inner shell 3 into two chambers 7 and 9. To permit the gases to pass from chamber 7 to 9 a metal structure 10 forming a plurality of conduits 11 (see Fig. 2) is located around the inner surface of inner shell 3. The gases passing from conduits 11 out to chamber 9 are eliminated by passage through exhaust outlet tube 12. The device is a silencer as well as a waste heat boiler, all as disclosed in its various forms in our aforesaid previous application, and due to the low temperature of the exhaust gas will operate as a silencer without danger even when the water jacket is completely dry.

20 Attached to said boiler outlet pipe 6 is a cross-over pipe 14 (Fig. 1) leading to the upper portion of a drum 15. In this pipe 14 is a pressure reducing valve 16 of any suitable construction. The top of drum 15 is provided with a steam outlet 17 which is connected by the drum to pipe 14 and which leads to any suitable mechanism provided to utilize the steam supplied. Drum 15 also has a safety valve 21 set in the top thereof. The bottom of the drum connects with the inlet pipe 5 by conduit 18. A blow-off valve 19 is provided at the end of conduit 18 beyond its connection with inlet 5. The return of steam condensate from the system supplied, if the apparatus is adapted (as in Fig. 1) for a pump return system, is by return line 20 to the lower portion of drum 15 through a water feed device 23, preferably of the usual float chambered construction, which maintains the water in the drum 15 at a minimum level (line A—A). If the apparatus were joined to a gravity return system then return line would be coupled to the system at the elbow connection of conduit 18 and inlet pipe 5. This type of connection has been illustrated in the modification of Fig. 3 where return line 20' is joined to the elbow of pipe 5 and conduit 18.

It will be understood that there are also various possibilities with respect to the relative arrangement of the drum, the reducing valve control and the boiler. The arrangement seen in Fig. 3 shows different changes which can be made to vary the structure of Fig. 1. The waste heat boiler is here arranged in a vertical position and the drum 15 is located so that its water line is 55 below the top of the boiler. In addition the

pressure reducing valve 16 is made responsive to conditions somewhere in the line 17, as by a thermostatic device located in any desired place, as at 25, instead of in the top of drum 15 as in Fig. 1. This location of the thermostat control is particularly adaptable to the de-superheating arrangements discussed below. The use of any one or more of the variations enumerated is guided largely by considerations of convenience in operating the apparatus for a particular purpose or in a particular place.

Referring now to the operation of the device, the automatic control apparatus is designed to utilize only so much of the heat from the exhaust gases as is convenient for the necessities of the system to which it is coupled through outlet 17. The drum 15 contains the water supply fed to the jacket 4 of the boiler through inlet 5. Water in jacket 4 is heated by contact with the outer surface of shell 3, which receives heat directly from the hot gas in passages 11 and also by conduction from the metal structure 10 which is heated both by the gas within passages 11 and by the gas in chambers 7 and 9. A very large metal to gas contact surface is thus available. The water is vaporized into steam which rises through outlet pipe 6 to the upper portion of drum 15 and out through conduit 17. When the steam pressure builds up in drum 15 to an amount predetermined by the reducing valve 16 and enough to satisfy the demand for steam, the pressure reducing valve is set to begin closing off the supply by blocking the cross-over pipe 14. Steam is however still being generated in the jacket 4 and consequently the pressure commences to rise in the boiler. As the pressure increases it causes the water in the jacket 4 to be forced back through pipe 5 and conduit 18 into the drum 15. The rise of water in the drum will continue until the head of water and steam pressure therein balances the increased pressure in the boiler. The water receding from the jacket of the boiler lessens the amount of water available for conversion into steam because the area of contact between water and heating surface is thereby decreased. Consequently, less steam is generated when the demand for steam becomes less.

It will be apparent that the pressure in jacket 4 determines the amount of water fed to it so that an excess amount cannot enter to create explosive pressures by flashing to steam. When there is a complete shut off with no demand for steam, any excess pressure in the drum caused by the water backing up into it may be relieved by the safety valve 21. When enough water is forced out of the jacket to uncover all of the outer surface of shell 3, no more heat is transferred to the water and, therefore, no more steam is generated. The pressure then in the jacket has reached its maximum which is the closing pressure of the reducing valve 16 plus the total head in the drum.

As the pressure drops in the drum below the closing point of the valve, due to an increase in steam demand, the pressure reducing valve opens, allowing steam to escape from the heating section 4 to supply the demand. As steam leaves the heating section through pipe 6, the pressure in jacket 4 will drop allowing the water to rise and come in contact with more heating surface and thereby generate more steam to meet the increased steam demand.

The drum 15 has a capacity above the minimum water line somewhat in excess of that nec-

essary to hold the entire water content of the boiler under the condition where no steam is needed. This excess capacity is provided to assure that the water in the drum will at no time interfere with the connection between steam outlet 17 and the cross-over pipe 14, nor obstruct the safety valve connection in the top of the drum.

It will be noted that the reducing valve 16 may be controlled from various points, according to the use to which the waste heat utilizer is put. It may be regulated manually or automatically by steam-pressure led from the drum 15 through a connection 24 (Fig. 1), or from a thermostatic device 25 located either in line 17 (Fig. 3) or wherever the temperature control is desired.

As the steam demand decreases less water is carried over by the steam until a point is reached where only dry saturated steam is delivered. From this point onto a no demand condition, superheated steam will come over. It is theoretically possible that at very low load the steam can be superheated to a temperature very close to that of the exhaust gases. Highly superheated steam requires special piping and fixtures and it is therefore desirable to keep the degree of superheating to a reasonable minimum. In Fig. 4, the steam supplied to the drum 15 is discharged beneath the water level in the drum by an extension 26 of the cross-over 14. The steam is thus forced to bubble up through the water thereby reducing its super heat. It is desirable to include a trap 27 in the cross-over 14 to prevent water backing into the steam generator. The cross-over 14 could open directly to the bottom of the drum 15 as shown in Fig. 5 but since it is desirable to have the cross-over drain to the drum, the arrangement of Fig. 4 is preferable. In the arrangement of the latter figure the pressure reducing valve 16 may if desired be installed in the drum at the end of extension 26 as shown at 28 in Fig. 6. Fig. 4 also shows a modification of the return line of valve in reducing the tendency of large quantities of water to enter the boiler suddenly, which if the water is cool would cause a lag in the supply of steam demanded or if the water is hot might cause undesirable flashing into steam. A check valve 35, permitting free flow away from the boiler, is placed in line 5, while a by-pass 36 around this check valve is provided with a fixed or adjustable throttle 37. A leaky check valve of standard type will perform the same function. Flow from the boiler to drum 15 is unrestricted, while water can flow into the boiler only at the rate fixed by the setting of throttle 37.

Additional reduction of the superheat may be secured by causing the steam to travel through a section of coiled pipe submerged in the water of the drum, as shown in Figs. 7 and 8. In Fig. 7 the steam is discharged directly to the drum 15 and enters the open end 29 of coil 30 which end is above the maximum water level in the drum. The lower end of coil 30 is connected to the steam discharge pipe 17 leading to the steam utilizing system. In the arrangement of Fig. 8 the cross-over 14 connects directly with the upper end of the coil 30, the lower end of the coil being connected to a pipe 31 which delivers the steam to the upper part of the drum. In Fig. 8 the pressure-reducing valve 16 is placed in pipe 31. Since the conditions tending to superheating of the steam occur when the water level in the drum is rising, the length of submerged travel of the steam in the arrangements of Figs. 4 to 8 in-

increases as the degree of superheat tends to increase.

Preferably, and as shown in the several arrangements disclosed in Figs. 1 to 8 inclusive, the steam line from the boiler to the steam utilizing system includes both the valve 16 and the drum 15, that is, the steam going to the utilizing system passes through cross-over 14 reducing valve 16 and drum 15 on its way to the supply pipe 17. This arrangement has the advantage that the steam separation takes place in the drum and permits the use of the water in the drum for reducing the degree of superheating of the steam, in the manner above described. Another arrangement is shown in Fig. 9 in which drum 15 serves only as a water control space and the steam separation takes place only in the boiler jacket. The steam supply pipe 17 may be connected directly to the boiler as shown in Fig. 9.

We claim:

1. A waste heat utilizer having a water jacketed shell and conduits for conducting exhaust gases in heat transferring contact with the shell, and an automatic control for regulating the amount of heat utilized, said control comprising a water drum connected at its bottom to a low point of said jacket and near its top to a high point of the jacket, said latter connection having a pressure reducing valve therein responsive to steam pressure in the top of the drum, and means to conduct steam from the drum.

2. A waste heat utilizer having a boiler and conduits for conducting exhaust gases in heat transferring contact therewith and an automatic control for regulating the amount of heat utilized, said control comprising a water drum connected to a low point of said boiler and also having a connection to a high point of the boiler, said latter connection having a pressure reducing valve therein responsive to steam pressure in the top of the drum, and means to conduct steam from the drum.

3. Means for controlling the steam output of a waste heat boiler which comprises a chamber located externally of the boiler, a water line connecting the lower portion of the chamber and the lower portion of the boiler, the chamber having a capacity in excess of the water capacity of the boiler, a steam supply line from the boiler for connection to a steam utilizing system to be served by the boiler and including said chamber, a pressure reducing valve in the steam supply line located between the boiler and the part of the steam supply line leading to the utilizing system, and means responsive to a variation in the steam pressure in the steam supply line to adjust the opening in said pressure reducing valve.

4. Means for controlling the steam output of a waste heat boiler which comprises a chamber located externally of the boiler, a water line connecting the lower portion of the chamber and the lower portion of the boiler, means maintaining a minimum water level in the chamber, the chamber having a capacity above said minimum water level in excess of the water capacity of the boiler, a steam supply line from the boiler to the chamber, a steam supply line from the chamber for connection to a steam utilizing system to be served by the boiler, a pressure reducing valve in the steam supply line from the boiler to the chamber and located between the boiler and the steam supply line to the steam utilizing system, and means responsive to a predetermined steam pressure in the chamber and steam supply

line to the utilizing system to close said reducing valve.

5. Means for controlling the steam output of a waste heat boiler which comprises a chamber located externally of the boiler, a water line connecting the lower portion of the chamber and the lower portion of the boiler, means maintaining a minimum water level in the chamber, the chamber having a capacity above said minimum water level in excess of the water capacity of the boiler, a steam supply line from the boiler to the chamber, said steam supply line opening below the minimum water level of the chamber, a steam supply line from the chamber for connection to a steam utilizing system to be served by the boiler, and a pressure reducing valve in the steam supply line from the boiler to the chamber.

6. Means for controlling the steam output of a waste heat boiler which comprises a chamber located externally of the boiler, a water line connecting the lower portion of the chamber and the lower portion of the boiler, means maintaining a minimum water level in the chamber, the chamber having a capacity above said minimum water level in excess of the water capacity of the boiler, a steam supply line from the boiler to the chamber, a portion of said supply line being submerged below the minimum water level in the chamber, a steam supply line from the chamber for connection to a steam utilizing system to be served by the boiler, and a pressure reducing valve in the steam supply line from the boiler to the chamber.

7. Means for controlling the steam output of a waste heat boiler which comprises a chamber located externally of the boiler, a water line connecting the lower portion of the chamber and the lower portion of the boiler, means maintaining a minimum water level in the chamber, the chamber having a capacity above said minimum water level in excess of the water capacity of the boiler, a steam supply line from the boiler to the chamber said supply line having a portion submerged below the minimum water level in the chamber, a steam supply line from the chamber for connection to a steam utilizing system to be served by the boiler, and a pressure reducing valve in the steam line from the boiler to the chamber and located below said minimum water level.

8. Means for controlling the steam output of a waste heat boiler which comprises a chamber located externally of the boiler, a water line connecting the lower portion of the chamber and the lower portion of the boiler, means maintaining a minimum water level in the chamber, the chamber having a capacity above said minimum water level in excess of the water capacity of the boiler, a steam supply line from the boiler to the chamber, a steam supply line from the chamber for connection to a steam utilizing system to be served by the boiler, a portion of said last named line being submerged below the minimum water level in the chamber, and a pressure reducing valve in the steam line from the boiler to the chamber.

9. Means for controlling the steam output of a waste heat boiler which comprises a chamber located externally of the boiler, a water line connecting the lower portion of the chamber and the lower portion of the boiler, the chamber having a capacity in excess of the water capacity of the boiler, a steam supply line from the boiler for connection to a steam utilizing system and

including said chamber, a pressure reducing valve in said supply line between the boiler and the chamber, and means responsive to an increase or decrease in pressure in the steam supply line on that side of the pressure reducing valve towards the boiler to respectively decrease or increase the opening through said valve.

10. Means for controlling the steam output of a waste heat boiler which comprises a chamber located externally of the boiler, a water line connecting the lower portion of the chamber and the lower portion of the boiler, the chamber having a capacity in excess of the water capacity of the boiler, a steam supply line from the boiler for connection to a steam utilizing system and including said chamber, a pressure reducing valve in said steam supply line between the boiler and said chamber, and means responsive to an increase or decrease in pressure in the steam supply line on that side of the pressure reducing valve remote from the boiler to respectively decrease or increase the opening through said valve.

11. Means for controlling the steam output of a waste heat boiler which comprises a chamber located externally of the boiler, a water line con-

necting the lower portion of the chamber and the lower portion of the boiler, the chamber having a capacity in excess of the water capacity of the boiler, a steam line from the boiler to the chamber, a pressure reducing valve in said steam supply line, a steam supply line from the boiler for connection to a steam utilizing system, and means responsive to an increase or decrease in pressure in the steam utilizing system to respectively decrease or increase the opening through said valve, said last named steam line including at least a portion of said first named steam line and the pressure reducing valve.
